UNITED STATES PATENT OFFICE.

JOHN W. MILLET, OF DOLGEVILLE, NEW YORK, ASSIGNOR TO ALFRED DOLGE, OF SAME PLACE.

FULLING-MACHINE.

SPECIFICATION forming part of Letters Patent No. 448,535, dated March 17, 1891.

Application filed August 7, 1890. Serial No. 361,276. (No model.)

To all whom it may concern:

Be it known that I, JOHN W. MILLET, a citizen of the United States, residing at Dolgeville, in the county of Herkimer and State of New York, have invented new and useful Improvements in Fulling-Machines, of which the following is a specification.

This invention relates to improvements in fulling-machines; and the invention consists in the details of construction set forth in the following specification and claims and illustrated in the accompanying drawings, in which—

Figure 1 is a section along $x x$, Fig. 2. Fig. 15 2 is a plan view of a fulling-machine embodying my invention.

In the drawings, the letter A indicates a frame or support having a driving-shaft B, provided with the usual fast and loose pulleys C C. The shaft B has a gear D, engaging a gear E. The shaft of gear E has crank-pins F, oscillating the links or pitmen G, which actuate the oscillating arms H, suitably jointed or pivoted to the support. The 25 arms H are connected by links or pitmen I to the slides K, carrying the shaft L, on which swing the arms M, carrying the clamp N O. The screw P is adapted to force the clamp part O against the part N, so as to engage one 30 end of the felt Q. The other end of the felt is engaged by strips or rods R, across which is placed a bar S, onto which act the screws T, so as to force the strips R against the felt.

The felt rests in a tray or trough U, holding hot water and soap. The water may be kept hot by any suitable means, such as a heating-pipe a, connected at one end with a supply-pipe b for the inlet of a heating-fluid, and at the opposite end with a discharge-pipe b'. If the heating-pipe a is employed, it is 40 preferably extended along the bottom wall of the tray or trough U.

When the slides K, with the clamp N O, are moved back and forth, the felt will be 45 rolled or fulled. The clamp N O or its arms M are provided with one or more weights V, supported by arms W. By adjusting the weight nearer to or farther from the clamp N O the pressure of the clamp on the felt under 50 treatment will be varied in intensity as required by the work to be done.

If it be desired to vary the throw of the

arms H, this can be effected by rendering the crank-pins F adjustable relatively to the axis of the gear E by any of the usual devices employed for adjusting crank-pins. For instance, the crank-pins F may each be carried by a plate E', having slots E², and adjustably held by set-bolts E³, passing through the slots and engaging the gear E, as indicated by dotted lines, Fig. 1, so that by adjusting the plates E' the crank-pins can be moved to the position desired in relation to the axis of the gear.

What I claim as new, and desire to secure 65 by Letters Patent, is—

1. In a fulling-machine, the combination, with a reciprocating clamp made to engage one end of the felt, of holding mechanism, substantially as described, for engaging the other end of the felt, and a tray or vessel in which said clamp moves, substantially as described.

2. In a fulling-machine, the combination, with a reciprocating clamp made to engage one end of the felt, of holding mechanism for the other end of the felt, said holding mechanism consisting of engaging-strips R and a clamping-screw made to act on said strips, and a tray or vessel, substantially as described.

3. In a fulling-machine, the combination, with a reciprocating clamp made to engage one end of the felt and an adjustable weight secured to the clamp for regulating the pressure on the felt, of holding mechanism, substantially as described, for the other end of the felt, and a tray or vessel, substantially as described.

4. In a fulling-machine, the combination, with a reciprocating clamp made to engage one end of the felt, an oscillating arm for moving the clamp, and a crank-pin F and link or pitman G for actuating said arm, of holding mechanism, substantially as described, for the other end of the felt, and a tray or vessel, substantially as described.

In testimony whereof I have hereunto set my hand in the presence of two subscribing witnesses.

JOHN W. MILLET.
